(57) **CLAIM**

The ornamental design for display screen or portion thereof with graphical user interface, as shown and described.

DESCRIPTION

FIG. 1 is a first embodiment of a display screen or portion thereof with graphical user interface.

FIG. 2 is a second embodiment of a display screen or portion thereof with graphical user interface; and,

FIG. 3 is a third embodiment of a display screen or portion thereof with graphical user interface.

The broken lines shown in the drawings illustrate portions of the display screen or portion thereof with graphical user interface that form no part of the claimed design.

1 Claim, 3 Drawing Sheets
